UNITED STATES PATENT OFFICE

2,553,671

CIGARETTE HUMIDOR AND DISPENSER

William J. O'Brien, Jr., Durham, N. C.

Application October 24, 1949, Serial No. 123,168

3 Claims. (Cl. 312—84)

1

This invention relates to a novel combined cigarette dispenser and humidor which is relatively simple in design and construction, inexpensive to manufacture in large quantities, attractive in appearance, easy to manipulate, and very efficient for its intended purpose.

An important object of this invention is to provide an attractive cigarette case that can be placed on a desk or table, that can retain a relatively large number of cigarettes, and that is provided with a novel, manually operated roller-type dispenser which removably retains a humidifying unit that prevents the cigarettes from drying out and that cooperates with the roller for dispensing the cigarettes from the case one by one as desired.

A further object of this invention is to provide a cigarette humidor and dispenser of the character described which includes a base member for supporting the cigarette holder or case which is substantially rectangular in shape and which includes side rims or edges for retaining cigarettes falling on the base and preventing the cigarettes from dropping off the base member. The base member is also provided with an arched platform beneath an exit slot in the cigarette holder or case which slopes from the center of the base downwardly toward the rim so that a cigarette dispensed from the case will roll toward any one of the rims, allowing for easy access to the dispensed cigarette.

These, together with various ancillary objects and features of the invention which will later become apparent as the following description proceeds, are attained by the device, a preferred embodiment of which has been illustrated, by way of example only, in the accompanying drawings, wherein:

Figure 1 is a front elevational view of the device;

Figure 2 is a side elevational view of the device;

Figure 3 is a top plan view of the device;

Figure 4 is a perspective view of the humidifying unit;

Figure 5 is a sectional view taken substantially in the plane of section line 5—5 of Figure 2;

Figure 6 is a sectional view taken substantially in the plane of section line 6—6 of Figure 1; and

Figure 7 is a sectional view taken substantially in the plane of section line 7—7 of Figure 1.

Specific reference will now be made to the drawings. In the several views, in the accompanying drawings and in the following specification, similar reference characters indicate corresponding elements throughout.

2

The present device may be fabricated of any suitable material but preferably of an attractively colored plastic. The device consists of a casing 10 which may be of any shape, but preferably substantially cylindrical, including a continuous end wall 12 having an axially extending exit slot 14 at its bottom end. The end wall 12 is secured to side walls 16 and 18, the end wall 12 being provided with an opening at its top end for receiving a closure plate or door 20 having a handle 22 thereon, the door resting upon the upper edges of the side plates 16 or 18, as will be readily apparent with reference to Figure 5.

Secured to the side plates 16 and 18 is a further pair of side plates 24 and 26, respectively, which have leg portions 28 and 30 which are, in turn, secured to a base member 32 for supporting the casing 10 on the base member. A rod 34 extends axially through the casing, the side walls 16 and 18, and the side walls 24 and 26 and serves to additionally secure the walls 24 and 26 to the walls 16 and 18, respectively. Also, a pair of rods 36 extend across the casing and are secured terminally to the side walls 24 and 26 and serve as end guards for the removable cover 20.

The leg portions 28 and 30 are provided with aligned apertures 38 and 40. A dispensing roller is provided which includes a tubular member 42 which is perforated as at 44 and which includes a terminal reduced portion 46 that extends through one of the apertures 40 and has a knob 48 secured to the end thereof. Thus, it will be seen that the tube 42 is rotatably retained in one of the legs through the aperture 40, and by virtue of the reduced portion 46, the tube cannot slip out of the legs. The tube 42 is further provided with a plurality of spaced disks 50 which extend partially into the exit slot 14, as shown clearly in Figure 6, the disks being provided with axially aligned recesses 52 for receiving a cigarette 54 which falls by gravity into the recesses 52 and, when the tube 42 is rotated, it will dispense the cigarettes from the casing 10 onto the base member 32.

Slidable in the tube 42 is a second tube 56 which is provided with a plurality of apertures 58 and a knob 60 at one end thereof. This inner tube 56 is partially filled with an absorbent material such as cotton 62 which is suitably saturated with a humidifying liquid, such as water. In order to non-rotatably retain the inner tube 56 within the outer tube 42 and to align the perforations 58 with the perforations 44 so

that the evaporated fluid may pass through the exit slot 14 and into the casing 10 to humidify the cigarettes therein, the following means is provided. The outer tube 42 is provided adjacent one end with a diametrically extending pin 64, see Figure 5, and the end of the humidifier tube 56 opposite the knob 60 is provided with an axially extending slot 66 for receiving the pin 64. When the humidifier tube 56 is slipped into the outer tube 42 and rotated so that the pin 64 slips into and engages the ends of the slot 66, the perforations 58 and 44 are automatically in alignment with each other and both the inner and outer tubes may be rotated together by means of the knobs 48 and 60 to dispense a cigarette from the casing 10 upon the base member 32. This construction also allows the inner humidifier tube 56 to be readily removed from the outer tube 42 for replacement of the absorbent or humidifying fluid.

The base member 32 is preferably substantially rectangular and extends somewhat beyond both sides of the casing 10. The front and rear edges of the base member 32 are provided with upstanding rims in the form of rods 68 and 70 which serve to engage a dispensed cigarette and prevent the latter from falling off the base member 32. The base member also includes a platform 72 which is so arcuated that it has a relatively elevated portion 74 directly beneath the dispensing roller and portions 76 and 78 which slope downwardly toward the rims 68 and 70. Therefore, when the roller is rotated so that one of the recesses 52 receives a cigarette 54 and the cigarette is dropped through the exit slot 14, the cigarette will fall upon the high portion 74 of the platform and roll along either of the inclined portions 76 and 78 toward one of the rims 68 or 70, where easy access to the cigarette may be had by the smoker.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

- 5 1. A cigarette humidor and dispenser comprising a casing, a base, legs for supporting said casing on and spaced from said base, an elongated exit slot in said casing adjacent said base, a dispensing roller rotatably mounted in said legs beneath said slot, and a humidifier removably retained in said roller, said roller including a perforated tube and spaced disks secured on said tube extending part way into said exit slot, said disks including aligned recesses for retaining and dispensing cigarettes through said exit slot, said humidifier including a second perforated tube received in said first-mentioned tube, a fluid-retaining absorbent in said second tube, and means for non-rotatably retaining said second tube in said first tube and for aligning the perforations in both of said tubes.
- 10 2. The combination of claim 1 wherein said second tube retaining means includes a diametrically extending pin in said first-mentioned tube adjacent one end thereof, and an axially extending slot in one end of said second tube for receiving said pin.
- 15 3. A cigarette humidor and dispenser comprising a casing, a base, legs for supporting said casing on and spaced from said base, an elongated exit slot in said casing adjacent said base, a dispensing roller rotatably mounted in said legs beneath said slot, and a humidifier removably retained in said roller, said roller including a perforated tube, said humidifier including a second perforated tube received in said first-mentioned tube, a fluid retaining absorbent in said second tube, and means for non-rotatably retaining said second tube in said first tube and for aligning the perforations in both of said tubes.
